UNITED STATES PATENT OFFICE

124,944

DESIGN FOR A MOTION PICTURE PROJECTOR

Jacobus Marinus Willem de Nooy, Eindhoven,
Netherlands, assignor, by mesne assignments,
to Hartford National Bank and Trust Company,
Hartford, Conn., as trustee

Application June 13, 1940, Serial No. 92,977

Term of patent 7 years

To all whom it may concern:

Be it known that I, Jacobus Marinus Willem de Nooy, a subject of the Queen of the Netherlands, residing at Eindhoven, Kingdom of the Netherlands, and whose post office address is Emmasingel 29, Eindhoven (Holland), have invented a new, original, and ornamental Design for a Motion Picture Projector, of which the following is a specification, reference being had to the accompanying drawing, forming part thereof.

Figure 1 is a front perspective view and Figure 2 is a rear perspective view of a motion picture projector, showing my design, the top being plain.

I claim:

The ornamental design for a motion picture projector, as shown and described.

JACOBUS MARINUS WILLEM DE NOOY.
